[57] **CLAIM**

The ornamental design for a camera, as shown and described.

DESCRIPTION

FIG. 1 is a top, front, and right perspective view of a flash embodiment of the camera, showing the design.

FIG. 2 is a front view of the camera.

FIG. 3 is a top view of the camera.

FIG. 4 is a left side view of the camera.

FIG. 5 is a right side view of the camera.

FIG. 6 is a back view of the camera.

FIG. 7 is a bottom view of the camera; and,

FIG. 8 is a front view of a non-flash embodiment of the camera.

The undisclosed top, bottom, rear and side views in the non-flash embodiment are identical to those shown in the flash embodiment.
